US00D772972S

(12) **United States Design Patent** (10) **Patent No.:** **US D772,972 S**
Anari, III et al. (45) **Date of Patent:** **** Nov. 29, 2016**

(54) **HAND GRIP**

- (71) Applicant: **AR2 Products LLC**, Pompton Plains, NJ (US)
- (72) Inventors: **Anthony F. Anari, III**, Sussex, NJ (US); **Ryan Paul Vosburg**, Riverdale, NJ (US); **Russell Van Zile, III**, Riverdale, NJ (US)

(**) Term: **15 Years**(21) Appl. No.: **29/527,956**(22) Filed: **May 22, 2015****Related U.S. Application Data**

- (63) Continuation of application No. 29/463,605, filed on Jan. 16, 2014, now Pat. No. Des. 730,429.
- (51) **LOC (10) Cl.** **16-05**
- (52) **U.S. Cl.**
USPC **D16/243**; D8/303

Primary Examiner — Vy Koenig(74) *Attorney, Agent, or Firm* — Day Pitney LLP(57) **CLAIM**

The ornamental design for a hand grip, as shown and described.

DESCRIPTION

FIG. 1 is a front elevational view of a hand grip showing our new design;

FIG. 2 is a rear elevational view thereof;

FIG. 3 is a front elevational view thereof;

FIG. 4 is a right side elevational view thereof; and,

FIG. 5 is a left side elevational view thereof.

The broken lines in the figures depict portions of the hand grip that form no part of the claimed design.

1 Claim, 3 Drawing Sheets(56)
